FUEL INJECTOR

Louis O. French, Milwaukee, Wis.

Application November 10, 1947, Serial No. 785,179

7 Claims. (Cl. 103—41)

1

The invention relates to liquid fuel injectors for internal combustion engines and more particularly to automatic fuel injectors in which the pump and nozzle are associated as a unit.

One of the objects of the invention is to provide an automatic fuel injector in which the stroke of the high pressure fuel pump is variably limited by the variable metering of a checking liquid in a chamber associated with the outer end of the operating piston and in which the fuel supplied to the fuel pump is continuously circulated through the operating piston to cool the same and serve as a lubricant for the inner ring carrying portion of said operating piston.

A further object of the invention is to provide, in an automatic injector having a fixed spray pattern, a metering member forming part of the operating piston but angularly adjustable relative to the spray nozzle to control a hydraulic checking liquid to vary the stroke of the high pressure fuel pump, the adjustment of said member being through means at the outer end portion of the injector and forming a part of the variable volume chamber for said checking liquid.

A further object of the invention is to provide, in an injector of the type above described, an operating piston of light weight construction and thus reduce any effects that may be occasioned by the high speed operation of the injector particularly those occurring when the injector comes to rest at the ends of its inward and outward strokes.

The invention further consists in the several features hereinafter set forth and more particularly defined by claims at the conclusion hereof.

In the drawings:

Fig. 1 is a vertical sectional view through a fuel injector embodying the invention;

Fig. 2 is a horizontal sectional view of the injector alone taken on the line 2—2 of Fig. 1;

Fig. 3 is an elevation view of the operating piston;

Fig. 4 is an elevation view of the metering control member;

Fig. 5 is a vertical sectional view through the operating piston showing certain modifications;

Fig. 6 is a diagrammatic view of an injector installation.

Referring to the drawings, the injector has the relatively fixed metal housing parts comprising a piston stop 8, cylinder 9, cap 10, and nut 11.

Stop 8 is a ring seating on an annular flange 12 formed in the head 13 of an internal combustion engine and having a valve seat surface 14.

The cylinder 9 has a preferably straight bore

2

15, a fuel inlet passage 16 connected with said bore by a port 17, a relief port 18, a shoulder or seat 19 at the outer end of the bore 15, and a threaded bore 20. For a fixed spray pattern, a threaded opening 21 for a key 22 is provided.

The cap 10 fits loosely in the bore 20, so that it may be shifted relative to its seat to center parts hereinafter described and is clamped in fluid-tight engagement with the seat 19 by a sleeve nut 11 engaging the bore 20. This cap has an inlet 23 for a cushioning liquid, preferably a lubricant, a conical bore 24 connected with a guide bore 25, a fuel outlet 26, and a threaded enlargement 27 at the outer end of the bore 25.

15 The above described housing is adapted to be clamped in assembled relation in the head 13 with the end of the cylinder 9 abutting the stop 8 by any suitable form of clamp (not shown).

Referring to Figs. 1 to 4 of the drawings, a fluid 20 pressure operated piston working in the cylinder 9 comprises an operating piston 28 and a checking piston 29. The operating piston 28, made up of one or more parts, is formed to provide a fuel pump barrel 30, a ring carrying part 31, a valve 25 housing 32, and an annular cooling space 33 between the parts 31 and 32. It may be formed as a one piece casting of suitable alloy steel, or it may be formed as shown of two sleeve parts, brazed or welded together, one of these parts including the barrel 30 and housing 32 and the other the part 31 in which instance the first mentioned sleeve part may be of alloy steel and the part 31 of cast iron, aluminum alloy, or magnesium alloy provided with grooves to receive the piston sealing means, such as the rings 34. The housing part 32 has a head portion 35 which is provided with a conical valve surface 36 of less diameter than the bore 15 to seat on the seat 14 to initially reduce the area exposed to the compressed gases in the engine cylinder and permit of rapid acceleration of the piston after leaving its seat. The housing 32 has a bore 37 joining the barrel 30 at a shoulder 38 and having its other end threaded 39 to receive a nozzle clamping sleeve nut 40, and it has a key slotted extension 41 in which the key 22 works.

The checking piston 29 may be of one or more pieces but preferably is formed of two metal sleeves 42 and 43 having a drive or press fit connection with each other, so that these sleeves can each be finished to fit other cooperative parts before they are united together. The sleeve 42 is differentially bored as shown, and its outer end is recessed to provide a V-shaped notch 44 providing control edges 45 and 46 cooperat-

ing with the relief port 18 to control the stroke of the piston and hence the amount of fuel delivered to the engine. The sleeve 43 has an inwardly extending flange 47 seating on a part of the barrel 30 and provided with diametrically disposed key slots 48 and passages 43'.

The valving and spray nozzle mounted in the housing 32 may be of a suitable construction, and as an example I have shown an apertured valve disk or seat 49, clamped against the shoulder 33 by a nozzle member 50 which is engaged by the sleeve nut 40. A fuel control discharge valve 51 is normally seated against the seat 49 by a spring 52 interposed between the head of said valve and a seat in a bore 53 of the member 50 which bore connects by a valve guide bore 54 with the spray orifices 55, the stem of the valve being flattened to permit fuel passage through bore 54.

A high pressure fuel plunger 56 works in the barrel 30 and controls the fuel inlet ports 57 in said barrel which are supplied with fuel from the space 58 between pistons 28 and 29.

For angularly adjusting the piston 29, a metering control member 59, having a valved head 60 seating on the seat 24 and a shank 61 rotatably mounted in the bore 25, has a cylindrical extension 62 provided with diametrically disposed key projections 63 slidably engaging the key slots 48 whereby rotation of member 59 rotates the piston 29. The inner end of the head 60 projects beyond the extension 62 to form a differential pressure area 64 to aid in holding said head in fluid-tight engagement with its seat on an increase in pressure in the checking fluid chamber 65 formed between the cylinder 9, cap 10, piston 29, and extension 62. To permit passage of fuel from the outer end of the bore 15 to the outlet 26 the head of the plunger 56 has a diametrically disposed groove 66 alined with a bore 67 in member 59 which connects with a cross bore 67' communicating with an annular groove 68 in the shank 61 alined with said outlet. A stuffing box 69 mounted in the bore 27 engages the shank 61 whose exposed outer end carries a crank arm 70 that may be oscillated manually or through suitable governor control.

The outer end of the plunger 56 has a self-centering abutting engagement with the head 60 which due to the self-centering connection of the cap 10 with the cylinder is also self-centering relative to the inner bore or wall of the piston 29 which slidably engages the extension 62, and as the piston 29 has its flange 47 spaced from the barrel 30, it is also self-centering in the bore 15 and independently of the part 31 of the operating piston. The self-centering of the above parts is of importance in securing good fits between the relatively slidably movable parts above described, and it also permits, if necessary, of an increase in diameter of that portion of the bore in cylinder 9 in which the piston 29 works to provide such a cross-sectional area to said piston working in the checking chamber as to reduce the magnitude of the pressure in the chamber 65 and thus guard against leakage losses of the checking fluid where the pressures in chamber 65 would be excessive if a straight bore 15 were used. Thus while a straight bore 15 is preferred, there may be instances in practice where this bore is formed of differential bores when the outer diameter of the piston 29 is greater than that of the part 31 of the operating piston for the reasons above mentioned.

A piston return spring 71 is interposed between the flange 47 of piston 29 and the head of

plunger 56 and acts to hold said plunger against longitudinal movement, head 60 against cap 10, piston 29 in abutting engagement with piston 28 and the conical surface 36 against seat 14.

Referring to Fig. 6, fuel is continuously circulated through the injector in any of its operating positions while the engine is running from a supply tank 72 connected by a pipe 73 with a low pressure pump 74 connected by a pipe 75, associated with a cooler 76, with the inlet 16 which connects with the lower end of the bore 15 through the port 17 delivering fuel to the space 58 at the inner end of the piston which is its hottest operating part, the fuel then flowing upwardly through the passages 43' to the outer end of the cylinder 9, thence through the groove 66 in the head of the plunger to the passages 67, 67', and 68 and outlet 26 to a pipe 77 leading back to the tank 72, the pipe 75 also being equipped with the usual strainers (not shown). Thus the fuel passing through the space 58 supplies the high pressure fuel pump with its charge, cools the piston and also lubricates the walls of the bore 15 in which the operating piston works.

The chamber 65 may be supplied with a checking fluid, preferably a lubricant, from a tank 78 that may have a supply connection with the relief port 18 where the spring 71 alone is used to control the time of the beginning of injection, but where a variable timing of injection is desired to suit varying compression pressures that may occur in the engine, the tank 78 connects by a pipe 79 with the inlet 23 through a suitable spring closed valve fitting 80, and the relief port 18 has a suitable spring closed needle relief valve fitting 81 connected by a return pipe 82 with the tank, the tension of the spring of said relief valve being adjustable to vary the time of injection by varying the pressure in the chamber 65 necessary to open said valve and start the movement of the operating piston. The valves 83 and 84 may be of any suitable construction, reference being made to my copending application Serial No. 592,675, filed May 8, 1945, now Patent No. 2,516,690, dated July 25, 1950, for a detailed showing of these valves. The tank 78 has been shown arranged for gravity feed, but any suitable low pressure pump may be associated with said tank, if desired, to supply checking fluid to the chamber 65. Should any seepage from the chamber 65 to the space 58 occur such seepage will be incorporated in the fuel and become a part of the fuel charge.

With the above construction, when the compression pressure of the engine is sufficient to overcome the loading of the spring 71 alone or the loading of the valve 80, when used, the piston structure above described is moved outwardly, its movement being accelerated as it moves off its seat 14, and when during this movement the plunger 56 laps the ports 57, fuel is compressed in the barrel 30 until its pressure is sufficient to overcome the tension of the spring 52 and lift the discharge valve 51 off its seat to allow fuel to flow through the spray orifices 55 into the combustion chamber C of the engine. When this outward movement of the piston reaches a point where the control edge 45 laps the relief port 18, the lubricant or liquid in the chamber 65 will act as a hydraulic stop to arrest further movement of said piston, and depending upon the angular setting of the piston 29 by the adjustment control member 59 will depend the extent of outward movement or stroke of said piston structure and hence the amount of fuel delivered to the engine.

by the high pressure fuel pump. On the release of pressure in the engine cylinder, the spring 71 returns the piston parts to their initial position.

When a fixed spray pattern is not desired as where a centrally located nozzle discharges in a symmetrically formed combustion chamber so that possible rotary shifting of the fuel jet or jets will not change the combustion characteristics, then the key 22 and the slotted extension 41 of the piston 28 may be omitted and the sleeve nut 49 dispensed with by a direct threaded connection of the nozzle member 56 with thread 39, or if further simplification of the piston structure is desired, it may be formed as shown in Fig. 5 wherein the piston 29 may be integral with the parts 31 and 32 of the operating piston and made of cast iron, or a suitable aluminum or magnesium alloy, and the high pressure pump barrel 30' of suitable alloy steel is a separate part mounted in the differential bores 83 and 84 and clamped in position by the nozzle member 85 which has a direct threaded connection with the thread 86 of the bore 85, the member 85 also having the valve surface 36' formed thereon corresponding in function to the surface 36 of the first described construction. In this form the flange 87 connects the piston 29 directly with the operating piston, and the keys 63 work in arcuate slots 88, similar to the slots 48 shown in Fig. 2, this piston having the same mode of operation as the first described form except that its parts turn as a unit.

I desire it to be understood that this invention is not to be limited to any particular form or arrangement of parts except in so far as such limitations are included in the claims.

What I claim as my invention is:

1. In an automatic fuel injector, the combination of a housing having a cylinder bore, a reciprocatory piston working in said bore in response to gases under compression, said piston having a high pressure fuel pump chamber, a pump plunger working in said chamber and held against longitudinal movement, a variable hydraulic stop means between said housing and the outer end of said piston to vary the stroke of said piston, said bore and said piston forming a cooling chamber extending to the inner end of said piston and separate from said stop means and operatively connected with said housing, and means for circulating fuel through said cooling chamber.

2. In an automatic fuel injector, the combination of a housing having a cylinder bore provided with a relief port, a reciprocatory piston working in said bore in response to gases under compression having an actuating piston portion, and a checking piston portion provided with a control edge angularly shiftable relative to said relief port, said actuating piston portion having a high pressure fuel pump chamber, a pump plunger working in said chamber and held against longitudinal movement, a variable volume checking fluid chamber at the outer end of said piston comprising said housing, said checking piston and a metering control member for angularly shifting said checking piston portion relative to said relief port to vary the volume of said chamber, said metering control member being operable from outside said housing and having a valved head seating on the outer end of said housing having a differential pressure area exposed to the fluid in said checking fluid chamber, and means for supplying fuel to said fuel pump chamber.

3. In an automatic fuel injector, the combina-

tion of a housing having a cylinder bore, a reciprocatory piston structure working in said bore in response to gases under compression comprising an actuating piston and a checking piston movable angularly relative to said actuating piston, said actuating piston having a high pressure fuel pump chamber, a pump plunger working in said chamber and held against longitudinal movement, a variable volume checking fluid chamber at the outer end of said piston comprising said housing, said checking piston and a metering control member for angularly adjusting said checking piston, said housing having a relief port and said checking piston having a control edge cooperating with said relief port to vary the volume of said chamber, and means for supplying fuel to said fuel pump chamber.

4. In an automatic fuel injector, the combination of a housing having a cylinder bore, a reciprocatory piston structure working in said bore in response to gases under compression comprising an actuating piston and checking piston having an inwardly extending flange rotatably mounted on a part of said actuating piston and provided with keyways, said actuating piston having a high pressure fuel pump chamber, a pump plunger working in said chamber and held against longitudinal movement, a variable volume checking fluid chamber at the outer end of said piston comprising said housing, said checking piston and a metering control member provided with keys engaging said keyways for angularly adjusting said checking piston, said housing having a relief port and said checking piston having a control edge cooperating with said relief port to vary the volume of said chamber, and means for supplying fuel to said pump chamber.

5. In an automatic fuel injector, the combination of a housing, a reciprocatory piston structure working in said housing in response to gases under compression comprising an actuating piston and a checking piston, said actuating piston having a high pressure fuel pump chamber, a pump plunger working in said chamber and held against longitudinal movement, a variable volume checking fluid chamber at the outer end of said piston structure comprising said housing, said checking piston and a metering control member provided with key projections, said checking piston comprising inner and outer sleeve members, said inner sleeve having a flanged portion rotatably mounted on a part of said actuating piston and provided with keyways engaging said key projections for angularly adjusting said checking piston, said housing having a relief port communicating with said checking fluid chamber and said checking piston having a control edge cooperating with said relief port to vary the volume of said chamber, and means for supplying fuel to said pump chamber.

6. In an automatic fuel injector, the combination of a housing having a bore and a cap at one end of said bore, a piston structure working in said bore in response to gases under compression comprising an actuating piston and a checking piston mounted for angular movement relative to said actuating piston and having a self-centering engagement with said bore and provided with a bore, an actuator rotatably mounted in said cap and having a cylindrical extension working in the bore in said checking piston and a keyed connection with said piston for angularly adjusting the same, said cap having a mounting in

said housing permitting self-centering of said actuator relative to said checking piston, said actuating piston having a high pressure pump chamber, a pump plunger working in said pump chamber, a spring interposed between said plunger and said piston structure for holding said plunger against longitudinal movement in self-centering contact with said actuator and for returning said piston, said housing having a relief port and said checking piston having a control edge cooperating with said relief port to vary the stroke of said piston structure, and means for supplying fuel to said fuel pump chamber.

7. In an automatic fuel injector as claimed in claim 1 wherein the piston includes a checking

5 piston and an operating piston connected together by a flange slotted to provide keyways and the hydraulic stop means includes a member provided with keys engaging in said keyways.
